CLAIM

The ornamental design for a tool holder assembly, as shown and described.

DESCRIPTION

FIG. 1 is a front, left, top isometric view;
FIG. 2 is a front, left, bottom isometric view;
FIG. 3 is a right side elevation view;
FIG. 4 is a left side elevation view,
FIG. 5 is a front side elevation view;
FIG. 6 is a back side elevation view;
FIG. 7 is an enlarged top plan view; and,
FIG. 8 is an enlarged bottom plan view.

The broken lines in the figures show portions of the tool holder assembly that form no part of the claimed design.

1 Claim, 7 Drawing Sheets
